GUSTAVE E. JACOBSON AND JOHN L. JACOBSON, OF NEWARK, NEW JERSEY.

BOILER.

1,326,198.

Specification of Letters Patent. Patented Dec. 30, 1919.

Application filed July 12, 1916. Serial No. 108,769.

To all whom it may concern:

Be it known that we, GUSTAVE E. JACOBSON and JOHN L. JACOBSON, subjects of the King of Sweden, and residents of Newark, 5 in the county of Essex and State of New Jersey, have invented certain new and useful Improvements in Boilers, of which the following is a specification.

This invention relates more particularly 10 to boilers in which coils of pipe are employed for obtaining an extensive heating surface, and more especially to such boilers for use in house heating.

The objects of the invention are to provide 15 such a boiler in which steam may be very quickly obtained; to obtain steam without having to bring the entire volume of water to boiling temperature; to obtain this result and yet not reduce the volume of 20 water employed; to prevent cracking the boiler; to provide a construction adapted to be made from wrought iron; to permanently seal the joints; to secure simplicity of construction and operation, and to obtain other 25 advantages and results as may be brought out in the following description.

Referring to the accompanying drawings, 30 in which like numerals of reference indicate the same parts throughout the several views,

Figure 1 is a front elevation of a furnace having a portion of the outer jacket of the boiler broken away;

Fig. 2 is a central vertical section of the 35 same, on line 2—2, Fig. 3, the coils beyond the transverse row of nearest ones being omitted for greater clearness, and

Fig. 3 is a diagrammatic underneath view 40 of the lower ends of the coils, a full showing of the individual coils for clearness.

In the specific embodiment of the invention illustrated in said drawings, reference numeral 1 indicates a furnace having an ash pit or base 2 surmounted by a boiler 3 with a fire grate 4 between, as is customary in the construction of furnaces. The boiler preferably comprises a cylindrical inner shell 5 and a cylindrical outer jacket 6 substantially coaxial and spaced 45 apart so as to leave an annular chamber 7 between them, see Figs. 2 and 3. At their upper ends, the shell and jacket are directed radially inward forming top portions 8, 9, respectively, which are spaced apart and 50 form between themselves a continuation of the chamber 7. A smoke flue 10 preferably

extends up through the middle of the top portions for the escape of the gases of combustion from the grate, and this smoke flue is attached to the top portions 8, 9 of the 60 shell and jacket with an impervious joint so as to prevent the escape of steam or water. The upper end of the smoke flue projects above the upper top portion 9, forming a collar 11 for attachment of the 65 usual stove pipe (not shown). A steam pipe 12 leads from the top of the boiler and a return pipe 13 leads to the bottom, Fig. 1, it being understood that with a fire on the 70 grate the water contained within the chamber 7 will be heated to boiling temperature and the steam thus obtained carried through pipe 12 for whatsoever purpose desired.

In order to obtain steam more quickly and to utilize more fully the heat from the fire, 75 we provide a plurality of coils within the inner shell 5 and at a sufficient distance above the grate to allow a fire to be made therebeneath. We have shown each coil as comprising a plurality of convolutions of 80 a single piece of pipe the lower end of which leads through the inner shell 5 and opens into the chamber 7 about midway of the height of the chamber; the upper ends of the coils also open into said chamber at or 85 adjacent to the top thereof, as next to be more particularly described. It will be observed from the drawings that the coils are arranged in two annular series, the upper or outlet ends of the coils 14 of the outer series 90 or series next to the inner shell opening into the chamber 7 through the vertical or side wall of the shell, and the coils 15 of the inner series having their upper or outlet ends 95 opening through the inner top wall 8 of the shell near the flue 10. It will be understood, however, that although this has been found to be the most convenient and efficient arrangement under conditions so far tried, the ends of the coils may be arranged otherwise if so desired. One coil 16 is at the middle of the boiler, and opens at its upper end 100 through the top wall 8 of the inner shell, also, like the coils 15 of the inner annular series.

Preferably the coils 14, 15 in the two annular series of coils are tilted, that is, arranged so their longitudinal axes are not vertical, but slope somewhat from such vertical position. The coils in each series are 110 tilted toward each other, so that one coil slopes over the next in the series which in

turn slopes over the next, and so forth around the entire series of coils. Furthermore, the ends of each coil preferably extend from the coil tangentially of the general cylindrical form of the coil at opposite sides thereof, and the holes in the vertical wall of the inner shell in which the ends of the coil are held are by preference arranged one on a vertical line directly above the other, as 10 clearly shown in Fig. 1. By this arrangement, each coil not only forms a continuous upwardly inclined passage for the heated water and steam to rise in, but also exposes all the convolutions of the coil to the rising 15 heat from the fire on the grate. Obviously, the upper ends of such coils as open through the top portion 8 of the inner shell have to be directed upwardly, but by retaining the bent part in substantially the plane of tangency, the inlet and outlet for the coils may 20 be retained in substantially a vertical plane. In the particular arrangement of coils shown, see Fig. 3, the coil at the center of the boiler is, out of necessity, arranged vertically or substantially so, since there is insufficient room to tilt it, but this is not 25 thought to be essential and may be varied if desired.

Around the smoke flue 10, between the top 30 portions 8, 9 of the outer and inner shell, is a shield 17 which overlies the upper ends of the coil outlets which open through the top portion 8, and prevents steam from striking as jets against the outer top portion 35 9. This shield bends downward at its periphery and is permitted to rest for support on the inner top portion 8 of the shell. The shield 17 with its depending periphery in conjunction with the top portion 8 of the 40 inner shell 5, forms a supplemental chamber of a smaller capacity than the annular chamber 7. The edge of the shield being much closer to the top portion 8 than the rest of the shield, a restricted outlet of less 45 capacity than the chamber formed beneath the shield is formed between the top portion 8 and the edge of the shield, and the water passing into this small chamber under pressure is thus spread in a thin sheet over the 50 top portion 8 so as to be quickly heated and vaporized. To permit the steam and water to pass from beneath the shield 17 into the chamber 7 and at the same time allow the depending periphery of the shield to rest 55 upon the top portion 8 of the inner shell for support, the peripheral edge of the shield is notched or serrated at 18.

In manufacture, the inner shell and outer jacket are bent up independently, as cylinders, out of sheet metal, of the diameters desired, and the smaller one flared at its bottom, providing a lower flange 19 substantially the width of the chamber 7 desired. Also this smaller cylinder has holes drilled 60 in it at proper places to receive the ends of

the coils which are welded in position. The top portion 8 is made separate from the cylinder and welded thereto, the smoke flue being welded to the top portion and the shield preferably welded to the smoke flue. By 70 virtue of the flange 19, the larger cylinder forming the jacket is welded and made integral with respect to the smaller cylinder or inner shell, and the top portion 9, connecting the outer shell and the smoke flue, 75 is welded to both of said parts, whereby an integral structure is obtained which may be of wrought iron and accordingly less likely to crack than cast iron, requires less metal and is light in weight. Obviously a doorway 20 for the introduction of fuel may be cut through the front of the boiler, and by welding suitable flanges 21 therearound to both the shell and jacket the chamber 7 is sealed thereat.

In use it will be understood that the boiler is filled with water to a level between the inlet and outlet of the coils, so that water stands in the coils for only part of their height. With a fire upon the grate, the water in the chamber 7 is heated, but the coils 14, 15, 16 being in the direct path of the heat becomes very hot quickly and steam will rise therein even before water in the chamber 7 is hot. By this means steam is 95 quickly emitted from the upper ends of the coils and filling the upper part of the chamber 7 is carried off by the pipe 12 for whatever purpose desired. Steam can thus be gotten up very quickly by our improved construction.

Obviously various modifications and changes may be made in the manufacture of our improved boiler and we do not wish to be understood as limiting ourselves except as required by the following claims when construed in the light of the prior art.

Having thus described the invention, what we claim is:

1. In a boiler, an inner shell and an outer jacket forming inside themselves a heating chamber and between themselves a water chamber having a lower vertical annular portion and an upper inward annular extension, a pipe in said heat chamber opening at its lower end into the vertical portion of the water chamber and opening at its upper end into the upper inward extension of said chamber, and an annular shield around the heat chamber in said upper extension of the water chamber and spaced from the floor thereof overlying the upper end of the said pipe, the peripheral edge of said shield being turned downwardly toward the floor of the said extension and co-operating therewith to form a restricted outlet of less capacity than the chamber beneath the shield to spread the water in a thin sheet over the floor of the said upper extension.

2. In a boiler, an inner shell and an outer jacket forming inside themselves a heat chamber and between themselves a water chamber having a lower vertical annular portion and an upper inward annular extension, a pipe in said heat chamber opening at its lower end into the vertical portion of the water chamber and opening at its upper end into the upper inward extension of said chamber, and an annular shield around the heat chamber in said upper extension of the water chamber and spaced from the floor thereof overlying the upper end of the said pipe, the peripheral edge of the said shield being turned downwardly and resting upon the floor of the said upper extension of the water chamber and forming a restricted outlet of less capacity than the chamber beneath the shield to spread the water in a thin sheet over the floor of the said upper extension of the water chamber.

3. In a boiler, an inner shell and an outer jacket forming inside themselves a heat

chamber and between themselves a water chamber having a lower vertical annular portion and an upper inward annular extension, a pipe in said heat chamber opening at its lower end into the vertical portion of the water chamber and opening at its upper end into the upper inward extension of said chamber, and an annular shield around the heat chamber in said upper extension of the water chamber and spaced from the floor thereof overlying the upper end of the said pipe, the peripheral edge of the said shield being turned downwardly and resting upon the floor of the said upper extension of the water chamber for support, said peripheral edge being notched to form a restricted outlet of less capacity than the chamber beneath the shield to spread the water in a thin sheet over the floor of the upper extension of the water chamber.

GUSTAVE E. JACOBSON.
JOHN L. JACOBSON.
